UNITED STATES PATENT OFFICE.

NATHAN F. BURNHAM, OF YORK, PENNSYLVANIA.

MEANS FOR LUBRICATING STEAM-ENGINES.

SPECIFICATION forming part of Letters Patent No. 336,838, dated February 23, 1886.

Application filed October 7, 1885. Serial No. 179,252. (No model.)

To all whom it may concern:

Be it known that I, NATHAN F. BURNHAM, a citizen of the United States, residing in the borough of York, in the county of York and State of Pennsylvania, have made certain new and useful Improvements in Means for Lubricating Steam-Engines, of which the following is a specification.

The object of my invention is to effect a perfect lubrication of the parts of the engine by gradual or drop-by-drop feeding of the oil to the parts when the engine is running.

The particular engine illustrated and described herein forms the subject-matter of another application for Letters Patent filed by me simultaneously herewith, and this application is confined to the lubricating devices. My present improvements, however, may be applied to engines differing in details of construction from that shown in the drawings.

In the accompanying drawings, Figure 1 is a transverse section of my improved engine; Fig. 2, a detail view showing the oiling devices for the main shaft; Fig. 3, a plan view 25 of the cross-head or slide-head with the pitman-rod and guide in section. Fig. 5 is a detached elevation of the slide-head; and Fig. 4 is a view, partly in section, showing the slide-head in the guide, the view being at right angles to that shown in Fig. 5.

A A are upright standards, four such standards—two at each end—being employed in this machine, and B is the cap-plate, which is securely bolted to the standards in any suitable 35 way. The steam-cylinder C is bolted to the under side of the cap-plate, and depends or is suspended therefrom. The piston-rod e passes through a stuffing box in the lower cylinder-head, and is secured to the slide-head D, which 40 works in the guide D'. The slide-head is formed with two depending lugs, d d, which carry a pin, f, on which the connecting-rod F has its bearing. These lugs slide in contact with the sides of the cylindrical guide D'. This 45 guide is cylindrical, and is slotted on its opposite sides, as shown in Fig. 4, and as may also be seen in Fig. 1, the latter figure being a section through the center of the slots. The upper face of the slide-head D is formed with a 50 vertical annular flange, g, which is covered by a plate, g', thus forming a shallow chamber,

which is filled with wool, cotton waste, or other absorbent material. Apertures h, formed in the vertical annular flange g, lead to oiling-grooves i on the exterior faces of the lugs d, 55 as clearly shown in Figs. 4 and 5. An oil-tank, K, is conveniently located—as, for instance, on the lower flange of the steam-cylinder—and has extending from its bottom a pipe, k, which terminates just over an aperture, k', in the cover-plate g' on the slide-head. The pipe k is filled with wicking, so that the lubricating material is delivered drop by drop into the aperture k'. The fibrous material in the chamber on top of the slide-head becomes 60 saturated, and the oil is fed little by little through the apertures h along the oiling-grooves i, thus thoroughly lubricating the bearing of the slide-head in the guide D'. A pipe, l, communicating with the oil-chamber on the top of the slide-head, extends through the head and projects below it, as clearly shown in Fig. 1. This pipe also contains a wick, the projecting end of which is in proper relation to the cup-shaped mouth of a tube, m, which 65 leads to the bearing of the connecting-rod pin f. As the connecting-rod oscillates, therefore, the oil will, drop by drop, be scraped from the end of the wick and the bearing kept constantly lubricated. The crank-pin or connection of the connecting-rod F with the main shaft is lubricated in a similar manner by oil 70 from a tank, N, from which a tube containing a wick depends in such relation to the sharp-edged mouth of a tube, O, carried by the connecting-rod and leading to the crank-pin bearing, that the oil is shaved from the end of the wick drop by drop upon each revolution of the crank. The bearings P on the main shaft 75 at each end of the casing are lubricated by oil 80 from a tank, Q, as clearly shown in Fig. 2. The casing of the engine R, where the main shaft passes through it, is bent or spun out into a hub-like projection, R', as seen in Fig. 2. The bearing of the shaft P extends into this 85 hub-like projection, and a sharp-edged collar or ring, S, fixed on the shaft, is interposed between the bearing and the side of the casing. By this construction oil is prevented from passing endwise along the shaft to the exterior of 90 the casing. It comes in contact with the sharp-edged ring S, and falling or being thrown 95 100

off from its periphery is drained off through a channel, *s*, into the oil bowl or receptacle *S'*, formed in the base of the engine.

I claim as my invention—

- 5 1. The combination of the slide-head, the oiling-chamber in the top of the slide-head, the oil-apertures *h*, and the oiling-grooves *i*.
2. The combination of the slide-head, the oiling-chamber formed in the top thereof, the 10 apertures *h* leading from said chamber, the oil-tank *K*, and the distributing-pipe *k*.
3. The combination of an oil-tube containing a filling of flexible or absorbent material which projects from the end thereof, and an oil-feeding tube carried by some moving part of the engine which sweeps past the end of the relatively stationary tube and scrapes the oil off at each movement of the part.
4. The combination of the slide-head, the 20 main shaft, the connecting-rod, the bearing of the connecting-rod in the slide-head and on the main shaft, an oil-feeding tube carried by the connecting-rod and leading to its upper bearing in the slide-head, a similar oil-feeding tube carried by the connecting-rod or by the 25 crank on the main shaft and leading to the bearing of the connecting-rod on the main

shaft, and relatively stationary oil-distributing tubes, having wicks projecting from the ends thereof placed in such relation to said oil-feeding tubes that the latter tubes sweep past the wicks and scrape the oil therefrom at each oscillation of the connecting-rod.

5. The combination of the slide-head, the oil-chamber formed in the top of the slide-head and packed with absorbent material, the oil-tank, a pipe through which oil is fed little by little to said chamber, an oil-pipe communicating with said chamber and leading to the underside of the slide-head and having a wick 35 projecting from the end thereof, and the movable oil-tube carried by the connecting-rod and leading to its bearing in the slide-head.

6. The combination of the main shaft, its bearing and oiling devices, the casing of the 45 engine, the sharp-edged ring interposed between the bearing and the side of the casing, and the oil-channel *s*.

In testimony whereof I have hereunto subscribed my name.

NATHAN F. BURNHAM.
